UNITED STATES PATENT OFFICE.

CLEMENT B. BISHOP, OF PHILADELPHIA, PENNSYLVANIA, ASSIGNOR TO
BENONI FRISHMUTH, OF SAME PLACE.

DESIGN FOR A SPECTACLE-FRAME.

SPECIFICATION forming part of Design No. 18,727, dated November 13, 1888.

Application filed September 27, 1888. Serial No. 286,603. Term of patent 7 years.

To all whom it may concern:

Be it known that I, CLEMENT B. BISHOP, a citizen of the United States, and a resident of Philadelphia, Pennsylvania, have invented a new and original Design for a Spectacle-Frame, of which the following is a specification.

My design is fully shown in the accompanying drawings, in which—

10 Figure 1 is a perspective view of sufficient of the frame to illustrate the design. Fig. 2 is a plan view of so much of the frame as is represented in Fig. 1; and Fig. 3 is a view similar to Fig. 1, but showing another form of the design.

15 The design comprises the end piece and its relation to the lens-frame and temple. The end piece, *a*, is of angular form and has the apex of one of its angles indented by the lens-frame *b*, and the temple *d* projects from one 20 of the straight or flat sides of the end piece

some little distance from the tip of said end piece.

In Fig. 3 the end piece is of hexagonal form, instead of being diamond-shaped, as in Figs. 1 and 2, the characteristic angular form of the 25 end piece, however, being the same in both cases.

I claim—

In a spectacle-frame, the design consisting of the angular end piece, lens-frame, and temple, occupying relations substantially as described, and as shown in the accompanying drawings.

In testimony whereof I have signed my name to this specification in the presence of two sub- 35 scribing witnesses.

CLEMENT B. BISHOP.
